UNITED STATES PATENT OFFICE

FRANK H. HEITGER, OF FLINT, MICHIGAN

CARBURETOR

Application filed July 23, 1928. Serial No. 294,917.

This invention relates to improvements in carburetors of the kind used on internal combustion motors in automotive vehicles.

The invention pertains to plain tube or Venturi type carburetors of the kind using an auxiliary fuel reservoir or well, and especially to such carburetors having variable level auxiliary fuel reservoirs containing an auxiliary fuel supply, that at the lowest speeds is to be drawn upon as the occasion requires, such as for acceleration purposes when opening the throttle from lowest speed position, when an auxiliary or abnormal supply of liquid fuel is needed to compensate for the sudden inrush of air into the carburetor. Such reservoirs have a vent or port above the static level, in order that atmospheric pressure may force the fuel out to the air-passageway of the carburetor.

One of the primary objects of the present invention is to combine with such auxiliary fuel feeding means, a device for preventing the flow of air through the auxiliary reservoir to the air conduit of the carburetor.

Another object is to combine with the auxiliary reservoir, a float operated valve designed to close the atmospheric vent or port of the auxiliary reservoir when the fuel level descends in the latter, in order to prevent the feed of air with the auxiliary fuel.

Another object, co-related to the above, is the provision of means to continue the feed of fuel into and through the auxiliary reservoir while the atmospheric vent is closed.

Other objects and advantages of the invention will in part be set forth while specifying the various features of construction and operation hereinafter contained.

Referring to the drawings hereto annexed, for a detailed description of the invention,

Fig. 1, is a vertical sectional view partly in elevation of one type of carburetor to which the invention may be applied.

Fig. 2, is a top plan view of a detail of the carburetor with certain parts omitted to facilitate illustration and showing the means for feeding fuel from the constant level supply reservoir to the auxiliary well.

Fig. 3 is a vertical sectional view taken on line 3—3 of Fig. 2.

Fig. 4 is a horizontal sectional view taken on line 4—4 of Fig. 3.

At the outset of this detail description it may be stated that the present invention can be applied to many types of carburetors, and for the purpose of disclosing the invention I have shown the same applied to a double Venturi type carburetor having a heated riser.

In the drawings 1 denotes the main air intake of the carburetor provided with a choke valve 2, which may be of the thermostatic controlled type. 3 designates the main fuel nozzle which discharges into an inner venturi 4, the air entering the latter at its lower end 5. The mixture of fuel and air formed in the inner venturi is discharged into the larger venturi 6 and there mixed with additional air which enters the lower end of the larger venturi. As before stated, this particular type of carburetor has a riser 7, which contains the pivoted throttle valve 8 and a heated fluid may enter this riser at the point 9, and be discharged at 10, the flow being controlled by a valve 11 that may be controlled thermostatically by means not shown.

The carburetor includes an idling jet or nozzle 12 which at certain positions of the throttle, feeds fuel into an idling duct 13 that discharges at 14 into the mixture passageway 15; it being understood that the mixture travels from 15 to the intake manifold of the engine.

16 indicates a constant level reservoir or flow chamber from which the fuel flows to the main and auxiliary nozzles and in traveling to the main nozzle it passes through a measuring jet or orifice member 17 into a chamber 18 which communicates with the main nozzle.

The auxiliary fuel fed to the main nozzle travels through a conduit 19 from (see Figs. 2 and 3) an auxiliary well 20, and also through 19 to the auxiliary reservoir in filling the latter.

This auxiliary well has a port 21 through which the auxiliary fuel flows from the well to the conduit 19, and the auxiliary well is fed by a pipe 22 which places the same in

communication with the constant level fuel supply 16, and is arranged below the normal fuel line A—A as shown in Fig. 3.

The reservoir 20 is provided with a cap 5 formed of two screw-threaded members 23 and 24, the latter having threaded engagement with the reservoir and the former having threaded engagement with the part 24. The part 23 includes a chamber 25 in which 10 a valve 26 moves, this valve being mounted on a stem 27 attached to a float 28 which is provided at its lower end with a guide plate 29 (see Fig. 4) having peripheral lugs 30, which engage the inner surface of the well 15 and serve to guide the float. The chamber 25 communicates with atmosphere through the port 31 and the chamber 25 communicates with the chamber 32 of the well by means of a port 33, which when the float is in its lower- 20 most position is closed by the valve 26.

When the engine is not running, the fuel from the main reservoir or constant level supply 16 will flow through the passageways 22 and 19 and fill the main nozzle and auxiliary well to the level A—A and at such time the float due to the fuel in the chamber 32 will occupy the position shown in Fig. 3 with the valve 26 bearing against the underside of the head of the cap member 23. At 25 this time, it may be stated, that the adjustment of the cap member 23 will permit greater or less vertical movement of the float and valve.

In operation, as soon as the engine is started and sufficient suction is obtained on the outlet end of the nozzle 3, fuel will be discharged therefrom and as the opening in the outlet is larger than the orifice in the measuring jet 17, fuel will be drawn from the auxiliary well. As the level of fuel in well 20 drops by discharge from the nozzle 3, the valve 26 will close port 33 and continued suction through port 21 by continued increase in motor speed, will finally cause 45 sub-atmospheric pressure in the well 20, and some fuel may be fed at such time through 22, 32 and 21 to the nozzle 3. This feed is desirable in some cases. As the port 21 is always opened there is a sub-atmospheric pressure established in the well after it is empty and this sub-atmospheric pressure, when the throttle is closed, suddenly draws fuel back into the well, owing to the then difference in pressure at the nozzle outlet and in the well. 50 This fuel will act on the float 28 and lift the same, unseating valve 26 and allow the level A—A to again be attained in the well. It is understood, of course, that the valve 26 and its port 33 are so formed as to be air tight, the suction on this valve, as stated, tending to seat it tighter, the greater the suction.

Referring to Fig. 4 it will be noted that the lugs 30 while guiding the float, permit the liquid fuel to flow past the float when necessary.

From the foregoing it may be seen that I have provided novel mechanism in which means are combined with an auxiliary fuel reservoir to prevent its feeding or bleeding air to the fuel feed while still retaining an auxiliary fuel feeding or supply means as for acceleration and low speeds with wide open throttle.

From the above it is believed that the construction, operation, and advantages of the invention may be readily understood by those skilled in the art and it is obvious that the parts or elements may be arranged in various positions and be made in various ways without departing from the spirit of the invention as set forth in the claims.

What I claim and desire to secure by Letters Patent, is:

1. In a carburetor having an air conduit, means for feeding fuel thereto including a constant level fuel reservoir, an auxiliary variable level fuel well supplied by the reservoir, said well having air inlet means and fuel outlet means, the fuel outlet means communicating with the air conduit, and means functioning upon a drop in level of the fuel in the well for closing said air inlet means.

2. In a carburetor having a carbureting passage, means for feeding fuel thereto from a constant level fuel reservoir by gravity from a restricted passage and normally subjected to atmospheric pressure, an auxiliary variable level reservoir receiving fuel from said constant level reservoir by gravity through a restricted passage, said auxiliary reservoir having an outlet for augmenting the supply of fuel to the carbureting passage and an air inlet and means controlled by the level of fuel in said auxiliary reservoir for closing and opening said air inlet.

3. In a carburetor having an air conduit, a constant level reservoir having means for feeding fuel to said air conduit, an auxiliary fuel reservoir having an air inlet and a fuel outlet supplied with fuel by gravity from said constant level reservoir, said fuel outlet communicating with said air conduit for augmenting the fuel supplied to said conduit and means including a float arranged in the auxiliary reservoir for closing said air inlet after fuel has been discharged from said auxiliary reservoir.

4. In a carburetor having an air conduit, a constant level fuel reservoir having means for feeding fuel to said air conduit, an auxiliary fuel reservoir having an air inlet and a fuel outlet supplied with fuel from said constant level reservoir by gravity, the fuel outlet of said auxiliary reservoir communicating with said air conduit for augmenting the fuel supplied to said conduit, a float in said auxiliary reservoir, a stem on said float and a valve on the stem to close the air inlet of said auxiliary reservoir when the fuel level in the reservoir drops.

5. In a carburetor having an air conduit, a constant level reservoir for feeding fuel to said conduit, an auxiliary reservoir receiving fuel from said constant level reservoir for
5 supplying fuel to said air conduit, said auxiliary reservoir having a cap provided with a chamber, an air inlet port and fuel outlet port for said chamber, a float in said auxiliary reservoir and a valve in said chamber
10 movable with the float and designed to close the air inlet port of said chamber when the float descends.

In testimony whereof I heretunto affix my signature.

15 FRANK H. HEITGER.
